UNITED STATES PATENT OFFICE.

HARRY C. WAITE, OF ELGIN, ILLINOIS, ASSIGNOR TO THERMO CARBURETOR CO., OF CHICAGO, ILLINOIS, A CORPORATION OF ILLINOIS.

CARBURETER.

1,381,681.

Specification of Letters Patent. Patented June 14, 1921.

Application filed September 10, 1917. Serial No. 190,462.

To all whom it may concern:

Be it known that I, HARRY C. WAITE, a citizen of the United States, residing at Elgin, in the county of Kane and State of Illinois, have invented a new and useful Improvement in Carburetors, of which the following is a specification.

The present invention relates to improvements in carbureters for internal combustion engines, and will be fully understood from the following description, taken in connection with the accompanying drawing, in which—

Figure 1 is a longitudinal central section 15 through a carbureter constructed in accordance with the invention and Fig. 2 is a fragmentary section on the line 2—2 of Fig. 1 and showing the auxiliary or starting carbureter and its attachment to the main carbureter.

The carbureter of the present invention is particularly designed for use with relatively heavy or non-volatile fuels and to that end comprises an auxiliary or starting carbureter of simple form and intended to handle a relatively volatile fuel for starting and warming up the internal combustion engine and a main or running carbureter for handling a non-volatile fuel and embodying adequate heating devices for insuring vaporization of the non-volatile fuel, the auxiliary carbureter and the main or running carbureter forming a single structural unit adapted for attachment in the usual manner to the intake manifold of the internal combustion engine.

Referring more particularly to the drawings, the numeral 10 designates the body casting of the main carbureter, this casting 40 having an open top central chamber 11 which constitutes the mixing chamber of the carbureter and alining air inlet and mixture outlet nipples 12 and 13, the latter being intended for connection to the inlet manifold of the engine. The inlet nipple 12 projects into the mixing chamber 11, the projection being in the form of a 45° elbow 14, the inner end of which is faced to form a valve seat for coöperating with a flap-valve 15 which swings upon a pintle 16 disposed horizontally in the body casting. One method of securing the flap-valve upon its pintle is illustrated in the drawings, the valve plate being here curved as shown at 17

to embrace the far side of the pintle while 55 a downturned tongue 18 bears upon the near side of the pintle. The valve 15 is normally held to its seat by a leaf-spring 19, one upwardly-curved end of which bears upon the outer face of the valve while the 60 other downwardly-curved end embraces a second horizontal pintle 20. A flat cover plate 21 which closes the open top of the mixing chamber and is secured thereto as by the screws 22, carries an adjustment 65 screw 23 which bears upon the upper face of the leaf-spring 19 adjacent the pintle of the latter.

The float chamber of the carbureter designated 24 is spaced some distance below the 70 body casting 10 being connected therewith by a tubular heater 25 having inlet and outlet nipples 26, 27, by which the exhaust gases of the internal combustion engine may be led through its bore. A depending boss carried by the top 28 of the float chamber extends below the normal liquid level therein and is bored to provide an air inlet passage 29 and a fuel outlet passage 30. The chamber connecting these two passages is closed 80 by a double-flanged stud 31 which also supports the bowl of the float chamber and carries the fuel nozzle 32. This nozzle member projects into the fuel passage 30 forming therewith an atomizing device for spraying 85 the liquid fuel. A thin walled tube 33 connects the bore 30 with the body casting 10 passing centrally through the heater 25 and terminating at approximately the level of the lower end of the flap-valve 15 within 90 the mixing chamber. The air inlet passage 29 is connected with the air inlet nipple 12 of the body casting by a similar thin walled tube 34. Outside of the point of connection with the tube 34, the nipple 12 may be provided with a butterfly-strangle valve 36 for shutting off the air supply of the carbureter. A similar butterfly valve 37 is arranged in the usual manner in the mixture outlet nipple 13 to control the supply of combustible 100 mixture to the engine.

The auxiliary carbureter, designated 38, is tapped into a threaded aperture 39 in the back wall of the mixing chamber of the main carbureter and comprises a float well 40, carbureting passage 41, nozzle 42 and throttle valve 43, all of these parts being of standard construction and requiring no particular de-

scription. Since the auxiliary carbureter is intended only for starting and initially warming the engine, it may be of very small size and of the simple form illustrated.

5 In the operation of my improved carbureting apparatus the float well 40 of the auxiliary carbureter is supplied with relatively volatile fuel, such as gasolene, while the float well 24 of the main carbureter is supplied 10 with relatively non-volatile fuel, such as kerosene. To start the internal combustion engine to which the carbureting apparatus is connected, the throttle valve 43 of the auxiliary carbureter is brought to the full 15 open position, any necessary controlling effect being obtained through the main throttle valve 37, the volatile fuel in the auxiliary carbureter is readily vaporized carbureting the air passing therethrough and 20 supplying this mixture to the mixing chamber 11 and thence to the connected internal combustion engine for starting the same and running without load or with very light load until the engine becomes heated up. Mean- 25 while, the jet 32 of the main carbureter will have been exposed to suction and a certain small quantity of the non-volatile fuel will have been drawn upwardly with the air passing through the heater tube 33. Ow- 30 ing to the thin walled construction of the tubes 33, 34, they will become heated to a relatively high temperature almost immediately after the engine is started and upon becoming heated will cause the vaporization 35 of the heavy fuel carried in suspension in the ascending current of air. As this vaporization becomes more complete, the mixture supplied to the engine will become richer and within a short interval of time it 40 is possible to close the throttle valve 43 of the auxiliary carbureter, the engine there- after operating upon the mixture of vaporized heavy fuel supplied by the main carbureter.

45 Under the suction of the engine the auxiliary or diluting air valve 15 will be drawn open against the resistance of the leaf-spring 19 to admit governed quantities of diluting air to the relatively rich mixture delivered 50 into the mixing chamber from the heater tube 33. In general, the tension of the spring 19 and the weight of the valve 15 will be such that the latter will open to a small extent even when the carbureter is supply- 55 ing the minimum quantity of the mixture, it being found desirable to proportion the carbureter parts so that under practically all conditions the mixture delivered into the mixing chamber from the heater tube 33 60 shall be over-rich, that is, shall contain a larger percentage of fuel than is required for combustion. Under normal operating conditions the volume of air supplied to the mixing chamber by the diluting air valve 65 15 far exceeds the volume of mixture sup-

plied by the heating tube 33, the latter be- 70 ing in effect therefore an oil-vaporizing tube through which a small quantity of air sweeps for the purpose of carrying along the vaporized oil. In general, it will be prefer- 75 able to preheat the air entering the main carbureting air inlet nipple 12, this pre- heating to be accomplished by connection of the nipple to a carbureter air heater of any common form. Under these operating con- 80 ditions, therefore, the entire mass of air ad- mitted to the carbureter is heated in the usual manner, and in addition a small pro- portion of this preheated air is utilized for aspirating and atomizing the fuel from the 85 nozzle 32, and sweeping the atomized fuel through the heating tube 33 and into the mixing chamber 11, where it meets the main stream of preheated air. The strangle valve 36 may be employed in the customary way 90 to temporarily increase the vacuum within the carbureter and provide a richer mixture to facilitate starting and warming up.

The normal or running adjustments of the carbureter are effected through the screw 23 95 which regulates the tension of the leaf- spring 19, thereby proportionately regulat- 100 ing the opening of the diluting air valve 15. By the spring arrangement shown, it is quite possible to provide a full range of adjust- 105 ment under a movement of one revolution or less of the screw 23, one extreme of this adjustment tensioning the leaf-spring 19 to such an extent as to hold the valve 15 closed under the highest operating suction, while the other extreme of the adjustment will per- 110 mit the valve to open to its full normal open- 115 ing without any resistance being offered by the spring. This full range of adjustment by a single turn or less of the screw 23 is rendered possible by reason of the relatively small movement of the spring under the full operative movement of the valve and by the 120 positioning of the adjustment screw adja- cent the supporting pintle of the spring.

It is to be noted that both the valve 15 and valve spring 19 may be bodily lifted from the carbureter upon the removal of the cover-plate 21. Each of these members has 180° or less bearing upon its pintle and may, therefore, be removed and replaced without disturbing any other parts of the mechanism. It is further to be noted that the nozzle 32 may readily be cleaned by the removal of the cover-plate 21 and spring 19, under which conditions it is possible to in- 125 troduce a cleaning wire or needle through the heating tube 33 and thence into and through the bore of the nozzle to remove any obstructions therein.

While I have shown and described in con- siderable detail one specific embodiment of my invention, it is to be understood that this is illustrative only and for the purpose of making the invention more clear and that I 130

do not regard the invention as limited to these details nor to any of them, except in so far as such limitations are included within the terms of the accompanying claims in 5 which it is my intention to claim all of the novelty inherent in my invention as broadly as is permissible in view of the prior art.

What I claim is:—

1. In a carbureter, a heater adapted to receive the exhaust gases of an internal combustion engine, a casing connected with said heater and having a mixing chamber therein, a main air passage leading to said chamber, a valve between the main air passage and 10 mixing chamber, a fuel inlet, a shunt air passage anterior to the valve and leading from said main air passage and terminating in an enlarged chamber surrounding the fuel inlet, and a passage leading from said last- 15 referred to chamber through the heating chamber and terminating in the mixing chamber posterior to the valve separating same from the main air inlet, whereby the fuel is heated in the presence of a small pro- 20 portion of air and then mixed with a larger 25 proportion of air at atmospheric tempera-
ture.
2. In a carbureter, a heater adapted to receive the exhaust gases of an internal combustion engine, a casing connected with said heater and having a mixing chamber therein, a main air passage leading to said chamber, a valve between the main air passage and mixing chamber, a fuel inlet, a shunt air passage of relative restricted area to the 30 main air passage and opening from the lower wall thereof anterior to the valve and leading from said main air passage and terminating in an enlarged chamber surrounding 35 the fuel inlet, and a passage leading from said last-referred to chamber through the heating chamber and terminating in the mixing chamber posterior to the valve separating same from the main air inlet, whereby the fuel is heated in the presence of a 40 small proportion of air and then mixed with a larger proportion of air at atmospheric 45 temperature.

HARRY C. WAITE.
